UNITED STATES PATENT OFFICE.

FRANK N. OSBORNE, OF NEW YORK, N. Y., ASSIGNOR TO THE TOWLE MANUFACTURING COMPANY, OF NEWBURYPORT, MASSACHUSETTS.

DESIGN FOR A SPOON OR SIMILAR ARTICLE.

SPECIFICATION forming part of Design No. 21,596, dated May 31, 1892.

Application filed April 25, 1892. Serial No. 430,637. Term of patent 7 years.

To all whom it may concern:

Be it known that I, FRANK N. OSBORNE, of the city, county, and State of New York, have invented a new and original Design for a Fork or Similar Article, of which the following is a full, clear and exact description.

Reference is to be had to the accompanying drawings, forming a part of this specification, in which the two figures represent, respectively, the obverse and reverse of a fork having my new design embodied in the handle thereof.

The design consists in the ornamentation shown, which comprises scroll-work and a beaded border, the latter following the contour of the handle. The handle is gradually enlarged from its base and then curved outward at opposite sides pronouncedly, as at b b , then inward, as at b' b' , and then slightly outward, as at b^2 b^2 , the extreme end of the handle having scallops b^3 . The scroll-work on the front of the handle at the end thereof consists of a figure formed of the two similar oppositely-disposed members c and a third small member c' . The most prominent figures of the end ornamentation are the horizontally-aligning convolutions c^2 c^2 . Spaced

from the end ornamentation by a plain surface d is a second series of foliate scrolls e , of which the minor members are subordinated to the longitudinally-aligning convolute figures e' e' . In connection with this second series of foliate scrolls conventionalized stems f appear, branching from the base of the handle in the direction of said scrolls e . In the treatment of the reverse of the handle a plain surface is in the main preserved and is only relieved by a single small scroll g g , branching inward at each side from the beaded edge g' and out of horizontal alignment, and a third small figure g^2 at the scalloped end of the handle.

I claim—

1. The design for a fork or similar article herein shown and described. 45
2. In a design for a fork or similar article, the obverse herein shown and described.
3. In a design for a fork or similar article, the reverse herein shown and described.

FRANK N. OSBORNE.
